UNITED STATES PATENT OFFICE.

JOEL E. HAWLEY, OF KANSAS CITY, MISSOURI.

MUSIC-LYRE.

1,057,381.

Specification of Letters Patent. Patented Mar. 25, 1913.

Application filed April 23, 1912. Serial No. 692,641.

To all whom it may concern:

Be it known that I, JOEL E. HAWLEY, a citizen of the United States, residing at Kansas City, in the county of Jackson and State 5 of Missouri, have invented certain new and useful Improvements in Music-Lyres; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to a lamp for music lyres and has for its principal object to provide a device for use by musicians when playing in parades, out-door concerts, or other places where it is impossible for them 20 to secure light by which to read their music, a further object of the invention being to provide a lamp which may be applied to the lyre, ordinarily carried by the instrument or on the body of the player, wherein the light- 25 ing current may be supplied from a battery carried in the pocket of a player.

In accomplishing these objects, I have provided the improved details of structure hereinafter described and illustrated in the 30 accompanying drawings, wherein:

Figure I is a perspective view of a lamp for music lyres constructed according to my invention. Fig. II is a rear view of same showing the mounting for the lamp. Fig. 35 III is a central vertical section on the line III—III Fig. II. Fig. IV is a cross section on the line IV—IV, Fig. II, showing the socket and the lamp stem.

Referring more in detail to the parts, 1 40 designates a music lyre of any ordinary construction, having the usual socket shank 2 and music rail 3.

4 designates a reflector having an open side 5 and a back portion 6 provided with 45 an insulation lined aperture 7. Extending through and mounted in the aperture 7 is a neck 8 of the lamp bulb 9, which latter is located within the reflector and is adapted for shedding light therefrom. The bulb 9 50 carries current wires 10 and 11, which lead

through a cord 12 to a battery 13, which may be carried in the pocket when the cord is of sufficient length to lead to such position from the mounting of the lamp on a music lyre.

While the lamp may be mounted on any 55 suitable lyre, I prefer to provide the back of the reflector with a stem 14 and the back of the lyre with a socket 15, which may be formed by depending lips 16 from the central ribs 17 of the lyre body, as illustrated 60 in Fig. II and Fig. IV.

Presuming the lyre to be adapted for receiving the lamp mount and the reflector to be constructed as described and equipped with a suitable lamp bulb, having connection 65 with the battery, the lamp may be carried in the musician's instrument case or in the pocket so that the lyre may be used in the usual manner where there is sufficient light by which to read the music. Should the 70 musician be called upon to play in night parades in the open air, or in any locality where there is insufficient light, the lamp may be mounted on the lyre by projecting the stem 14 of the reflector into the socket 75 15 of the lyre, when the reflector will extend out in front of the lyre with the open side down so that light from the bulb will be thrown onto the music carried by the lyre body. The cord 12 is usually long enough 80 to extend to the pocket of the musician so that the battery may be carried in the pocket. The battery may be provided with an ordinary switch, not shown, by which the 85 lamp circuit may be opened or closed.

It is apparent that with a device of this kind, a musician is independent of stationary lamps and that he is greatly benefitted by having a steady and sufficient light for his music when working in the open air or 90 in unlighted buildings.

Having thus described my invention, what I claim as new therein and desire to secure by Letters-Patent is:—

Claim:

The combination with a music lyre having a central body, of ears bent back from said body to form a socket, a reflector having a stem removably projected into said socket and having a cupped body portion projected 95 100

over the body of the lyre, a lamp located within the reflector and having a neck projected through the base thereof and insulated therefrom, and a portable battery having 5 flexible wire connection with the lamp substantially as and for the purpose set forth.

In testimony whereof I affix my signature in presence of two witnesses.

JOEL E. HAWLEY.
